Primary Examiner — Jeffrey D Asch*(74) Attorney, Agent, or Firm* — Carol N. Green, Esq.(57) **CLAIM**

The ornamental design for a mobile communication device, as shown and described.

DESCRIPTION

FIG. 1 is a top right perspective view of the mobile communication device shown in a switched-on, in-use state.

FIG. 2 is a top left perspective view of the mobile communication device shown in a switched-on, in-use state.

FIG. 3 is a bottom right perspective view of the mobile communication device.

FIG. 4 is a bottom left perspective view of the mobile communication device.

FIG. 5 is a top plan view of the mobile communication device.

FIG. 6 is a bottom plan view of the mobile communication device.

FIG. 7 is a right side view of the mobile communication device.

FIG. 8 is a left side view of the mobile communication device.

FIG. 9 is a rear view of the mobile communication device; and,

FIG. 10 is a front view of the mobile communication device. The mobile communication device includes an integral mouse-type controller that controls the mobile communication device and is capable of controlling at least one additional external mobile communication device.

The features shown in broken lines in FIGS. 1 and 2 indicate non-claimed displayed information.
